UNITED STATES PATENT OFFICE.

ARTHUR J. STONE, OF GARDNER, MASSACHUSETTS, ASSIGNOR TO FRANK W. SMITH, OF SAME PLACE.

DESIGN FOR A SPOON, &c.

SPECIFICATION forming part of Design No. 21,269, dated December 29, 1891.

Application filed October 29, 1891. Serial No. 410,283. Term of patent 3½ years.

To all whom it may concern:

Be it known that I, ARTHUR J. STONE, a citizen of the United States, residing at Gardner, in the county of Worcester and State of Massachusetts, have invented and produced a new and original Design for Handles for Spoons, Forks, Knives, and the Like, of which the following is a specification, reference being had to the accompanying drawings, showing a handle containing my said design, the handle being for spoons, forks, knives, and the like.

My design consists in a spoon or other handle ornamented with scroll-work and with clusters of fruit on a branch, which extends lengthwise the handle about midway between its edges toward its inner end, the outline of the handle when viewed in plan approximating that of the leaf of one variety of the lotus. The side edges a a' of the handle curve outwardly from the neck 1 of the handle to a^2 a^3 , respectively, and then inwardly at a^4 a^4 , and then outwardly at a^5 a^5 . At a^6 a^6 the side edges join the butt-end edge a^7 , each half (approximately) of which extends inwardly

and outwardly to a scroll a^8 at the extreme point of the butt-end of the handle and about in line with the lengthwise axis of the handle. The margin of the butt-end portion of the handle is ornamented with the scroll a^8 and conventionalized leaf-work a^9 a^9 . Each side margin is also ornamented with scroll-work a^{10} , and a conventionalized leaf-scroll a^{11} sweeps curvingly twice across that part of the handle which is between the swells a^3 a^3 and neck 1. From the open space between the marginal ornamentation on the broader or main part of the handle a branch a^{12} extends toward the inner end of the handle, running about midway the side edges and being ornamented with clusters a^{13} of fruit.

What I claim is—

The design for a handle for a spoon, fork, knife, or the like, as herein shown and described:

ARTHUR J. STONE.
